UNITED STATES PATENT OFFICE.

AUGUST A. STUTE, OF JACKSON, MICHIGAN.

COMBINATION SHIPPING-TAG AND MAILING-ENVELOP.

1,320,349.

Specification of Letters Patent. Patented Oct. 28, 1919.

Application filed March 17, 1919. Serial No. 283,076.

To all whom it may concern:

Be it known that I, AUGUST A. STUTE, a citizen of the United States, residing at the city and county of Jackson, State of Michigan, have invented certain new and useful Improvements in Combination Shipping-
Tags and Mailing-Envelops, of which the following is a specification.

This invention relates to a combination
10 shipping tag and mailing envelop.

The main object of this invention is to provide a container adapted as a mailing envelop or as a shipping tag facilitating the handling of C. O. D. parcel post matter, ex-
15 press, and the like.

Further objects, and objects relating to structural details, will definitely appear from the detailed description to follow.

I accomplish the objects of my invention
20 by the devices and means described in the following specification. The invention is clearly defined and pointed out in the claims.

A structure which is a preferred embodiment of my invention is clearly illustrated
25 in the accompanying drawing, forming a part of this specification, in which:

Figure I is a front view of a structure embodying the features of my invention.

Fig. II is a rear view thereof.
30 Fig. III is a detail view showing the manner of securing the attaching loops.

Fig. IV is an enlarged detail section on a line corresponding to line 4—4 of Figs. I and II.

35 In the drawing similar reference characters refer to similar parts throughout the several views.

Referring to the drawing, I provide an envelop-like container 1, preferably formed
40 of imitation leather, oil-cloth or other durable and preferably waterproof material, so that it may be used repeatedly and will withstand moisture and fully protect its contents.

45 The container is open at one end and is provided with a closure flap 2 having a slot 3 therein. The strap 4 is secured on the rear side of the container, as at 5. Both front and rear walls have slots 6 therein under the flap through which the strap may be passed
50 as shown in Fig. IV, the strap being then looped over the flap at 7 and passed through the slot 3 in the flap and its free end secured by means of the buckle 8. Thus arranged,
55 the container is securely closed, that is, it is

impossible for its contents to escape without the strap being unfastened and the strap may be passed around a part of the article which it is desired to tag or about the securing cord thereof as in a wrapped express 60 package or parcel post package.

To facilitate the attachment of the container to an article such as a box I provide the container with loops 9 projecting at its edges and adapted to receive staples or tacks 65 so that the container may be readily secured either by means of the strap or by the loops 9, tacks being used when it is desired to employ the device as a marking tag for a box, or if desired, attaching strings may be 70 passed through or secured to the loops 9.

The container is provided with a window 10 in its front side disposed so that the address on an inclosed sheet may appear there-through. In practice the statement or bill 75 of the shipper or an instruction sheet on which the name of the consignee appears so that it is visible through this window and constitutes the address for the tag.

The letters "C. O. D. to" are so associated 80 with the window that they constitute instructions to the Post Office Department or express company, and the words "Return with the remittance to" with the shipper's name will also appear, so that it is only necessary 85 in the case of parcel post packages, for instance, for the department to remove the tag or container from the package, remove the bill from the container, substitute there-for the money order, and return the container as an envelop through the mail.

The bill may be used as the office request and post office record for the money order or as a substitute for the usual money order request, or if desired, such request or instruction 95 may be inclosed by the shipper.

The containers are designed to be used repeatedly, thereby effecting a very large saving as the special shipping tags now commonly used in C. O. D. parcel post are quite 100 expensive, can be used but once, and are unsatisfactory in that they frequently become detached or the address blurred or defaced, so that it becomes impossible to read. The claims filed in the Post Office Department on 105 account of undelivered parcel post reaches an enormous figure annually, and further, much of the delay now incident to tracing parcel post packages would, by the use of these improvements, be obviated.

I have illustrated and described my improvements in one form in which I have embodied the same. I have not attempted to illustrate or describe other adaptations or modifications as I believe the disclosure made will enable those skilled in the art to which my invention relates to embody or adapt the same as may be desired.

Having thus described my invention, 10 what I claim as new and desire to secure by Letters Patent, is:

1. In a device of the class described, an envelop-like container adapted as a mailing envelop and as a shipping tag and having 15 an opening at one edge provided with a slotted closure flap and projecting loops at its other edges adapted to receive means for attaching the container to an article as a tag, and a strap and securing means there- 20 for on said container, said strap being adapted to be disposed over said flap and through the slot therein and engaged with its securing means with its bight projecting beyond the edge of the container as a means 25 for securing the container to an article as a tag so that the container may be attached to an article as a marking tag by either of said means or employed as a mailing envelop.

2. In a device of the class described, an 30 envelop-like container adapted as a mailing envelop and as a shipping tag and having an opening at one edge provided with a slotted closure flap, and a strap and securing means therefor on said container, said strap being 35 adapted to be disposed over said flap and through the slot therein and engaged with its securing means with its bight projecting beyond the edge of the container as a means for securing the container 40 to an article as a tag so that the container may be attached to an article as a marking tag.

3. In a device of the class described, an 45 envelop-like container adapted as a mailing envelop and as a shipping tag and having an opening at one edge provided with a closure flap and projecting loops at its other edges adapted to receive means for attaching the container to an article as a tag, so 50 that the container may be attached to an

article as a marking tag or employed as a mailing envelop.

4. In a device of the class described, an envelop-like container adapted as a mailing envelop and as a shipping tag and having 55 an opening at one edge provided with a closure flap and members adapted to receive means for attaching the container to an article as a tag, and a strap and securing means therefor on said container, said strap being adapted to be disposed over said flap as a securing means therefor and constituting a means for securing the container to an article as a tag so that the container may be attached to an article as a marking tag by 60 65 either of said means or employed as a mailing envelop.

5. In a device of the class described, an envelop-like container adapted as a mailing envelop and as a shipping tag and having 70 an opening at one edge provided with a closure flap, and a strap and securing means therefor on said container, said strap being adapted to be disposed over said flap as a securing means therefor and constituting a 75 means for securing the container to an article as a tag so that the container may be attached to an article as a marking tag or employed as a mailing envelop.

6. In a device of the class described, an 80 envelop-like container adapted as a mailing envelop and as a shipping tag having a closure flap at one edge, the front and rear walls having aligned slots beneath said flap, said flap having a slot therein, and a strap 85 secured to the rear wall of said container and adapted to be passed forwardly through the slots in said walls and folded over the flap and inserted through the slot therein and secured thereby constituting a securing 90 means for the container and a means for attaching the container to an article as a tag.

In witness whereof, I have hereunto set my hand and seal in the presence of two 95 witnesses.

AUGUST A. STUTE. [L. S.]
